UNITED STATES PATENT OFFICE.

HENRY A. FRAMBURG, OF CHICAGO, ILLINOIS, ASSIGNOR TO H. A. FRAMBURG & COMPANY, OF CHICAGO, ILLINOIS.

DESIGN FOR A BACKPLATE FOR AN ELECTRIC-LIGHT BRACKET.

Application filed August 21, 1923. Serial No. 7,047. Term of patent 7 years.

To all whom it may concern:

Be it known that I, HENRY A. FRAMBURG, a citizen of the United States, residing at Chicago, in the county of Cook, State of Illinois, have invented a new, original, and ornamental design for a Blackplate for Electric-Light Brackets, of which the following is a description, reference being had to the accompanying drawing, forming part hereof.

Figure 1 is a plan view of a backplate for an electric light bracket, showing my new design.

Figure 2 is a sectional view through Fig. 1. I claim:

The ornamental design for a backplate for an electric light bracket as shown.

In testimony whereof, I affix my signature.

HENRY A. FRAMBURG.
